TION OF CALIFORNIA.

TRACTOR-FRAME CONSTRUCTION.

1,317,654.

Specification of Letters Patent. Patented Sept. 30, 1919.

Application filed April 27, 1917. Serial No. 164,977.

To all whom it may concern:

Be it known that we, EMIL F. NORELIUS, of Peoria, county of Peoria, State of Illinois, and WILLIAM TURNBULL, of Peoria, county 5 of Peoria, State of Illinois, citizens of the United States, have invented new and useful Improvement in Tractor-Frame Constructions, of which the following is a specification.

10 This invention relates to tractor frame construction; and has for its object to provide a strong and rugged frame which will be light, simple and economical.

The construction includes a main frame 15 having its sides made up of composite truss beams, each comprising a sill with a tie-beam disposed above and plates or webs extending between and secured thereto, the sills being arranged for support upon a 20 truck mechanism at a point intermediate their ends and the tie-beams extending downwardly and forwardly from a point above said supporting connections; suitable cross connections being provided between 25 the sills and webs, near the front of the frame, to receive and support the motor and the cross connections being arranged near the rear of the frame between the tie-beams to receive and support the transmission 30 mechanism.

One form which our invention may assume is exemplified in the following description and illustrated in the accompanying drawings, in which—

35 Figure 1 shows a plan view of the main frame embodying our invention.

Fig. 2 shows a side elevation of the same.

Figs. 3, 4 and 5 show sectional views taken on the correspondingly numbered lines of 40 Fig. 2.

The frame comprises two longitudinal sills 10 of I-beam construction, connected together by cross-bars 11. Upon the sills is a superimposed frame, comprising longitudinally extending tie-beams 12, preferably of angle bar construction, extending from the rear of the main frame to a point near the front thereof, being through a considerable portion of their extent inclined downwardly 45 and forwardly. Between the tie-beams and sills are steel webs or plates 13, riveted to the flange of the angle bar above and connected to the top of the I-beam below by angular cleats 14.

The tie-beams 12 are connected together 55 by cross-bars 15, near their rear ends, and a longitudinally extending bar 16 is centrally arranged upon the cross-bars and additionally supported and reinforced by a diagonal brace 17, resting on a cross-bar 18 60 disposed between and connected to the upper faces of the sills 10. The cross-bars 15 and the longitudinal bar 16 form supports for the transmission and connected parts of the tractor mechanism. 65

At the front of the frame are transverse I-beams 19, resting upon the sills and connected to the webs by suitable cleats or angle plates, said transverse I-beams forming supports for the motor of the tractor. Near the 70 middle portion of the main frame are vertically spaced cross-bars 20, in the form of angle bars, connected to plates 21, which in turn are riveted to the webs 13 and to the I-beams beneath. Diagonally extending 75 space bars 22 arranged in the form of a cross are positioned below the cross-bars 20, and connected at their ends to the web portions of the I-beams. Beneath the I-beam sills, near the middle portions thereof, are 80 inverted channel bars 23 projecting at the sides to form connections for supporting the main frame upon the tractor truck mechanism. Suitable draft connections 24 are provided at the rear of the main frame, and 85 connected to the I-beam sills. Outrigger arms 25, at one or both sides, are connected to the webs 13, being adapted to receive and support a running board or shelf.

At the front end of the I-beams 10 is a 90 circle ring 26, secured in place to receive a turntable ring 27 to which the front wheels are connected.

The superimposed angle bars 12 and web plates 13 stiffen the frame against vertical 95 bending movement and form, in connection with the sill 10, a composite truss beam offering great strength and rigidity. The cross-beams 19, which support the motor, it will be noted, rest directly upon the sills 100 10, whereas the supports 15 and 16 for the transmission mechanism are connected to the tie-beams 12. This arrangement not only lends itself readily to the required 105 variation in the plane of the transmission mechanism and motor, thereby eliminating bed plates and spacer blocks, but also relieves the sills 10 of a considerable portion

of the bending strains that would be otherwise present. The sills 10 are adequately supported and reinforced at their central portions against relative, endwise movement 5 by the diagonal bars 22. The tie bars 12, it will be noted, start to incline downwardly and forwardly from a point overlying the channel supports 23 and, therefore, the long or forward ends of the beams 10 are stayed 10 against longitudinal bending by what, in effect, constitute angular braces which are effective both under tension or compression.

Various changes in the construction and arrangement of the several parts herein 15 shown and described may be employed without departing from the spirit of our invention as disclosed in the appended claims.

Having thus described our invention, what we claim and desire to secure by Letters 20 Patent is—

1. A main frame for tractors having its sides formed of truss beams, each including a sill to support said sides and a superimposed tie-beam, transverse bars at the front 25 resting on the sills to receive and support a motor, transverse bars at the rear connected to the tie-beams to receive and support the transmission mechanism, and transversely extending beams below the sills in- 30 termediate the motor and transmission supports for supporting connection with the truck mechanism.

2. A main frame for vehicles having parallel side members, each including a sill,

a web plate supported thereby and carrying 35 a superimposed tie beam, lateral beams for connecting the forward ends of the side members and forming a motor support, transverse bars connecting the tie beams at the rear of the frame for receiving a 40 transmission mechanism and a pair of spaced and parallel cross beams extending across and beneath the sills and overhanging the same for connection with the running gear.

3. A main frame for tractors, comprising 45 parallel side rails, each consisting of a continuous beam, a web plate secured to the upper face of the beam and a tie beam secured to the upper edge of the web plate, cross frame members rigidly connecting the 50 opposite ends of the sills, cross bars connecting the webs at the forward ends thereof for the support of a motor, cross bars connecting the webs at the rear end thereof for the support of a transmission, and a 55 pair of cross beams extending transversely of, and secured beneath, the side rails and overhanging the same to provide a support for the frame structure upon the vehicle running gear.

In testimony whereof we have hereunto set our hands in the presence of two subscribing witnesses.

EMIL F. NORELIUS.
WILLIAM TURNBULL.
